(57) **CLAIM**

What is claimed is the ornamental design for a headboard, as shown and described.

DESCRIPTION

FIG. 1 is a front view of an embodiment of a headboard showing my new design, the rear view being a mirror image thereof;

FIG. 2 is a right side view thereof, the left side view being a mirror image thereof;

FIG. 3 is a top view thereof;

FIG. 4 is a front view of another embodiment of a headboard showing my new design, shown broken away to indicate indeterminate width, the rear view being a mirror image thereof;

FIG. 5 is a right side view thereof, the left side view being a mirror image thereof; and,

FIG. 6 is a top view thereof.

FIGS. 4, 5 and 6 show that the width of the headboard of my design is indeterminate.
